UNITED STATES PATENT OFFICE.

GEORGE H. WHEARY, OF RACINE, WISCONSIN, ASSIGNOR TO THE HARTMANN TRUNK COMPANY, OF RACINE, WISCONSIN, A CORPORATION OF WISCONSIN.

WARDROBE GRIP OR TRAY.

1,025,351.

Specification of Letters Patent.

Patented May 7, 1912.

Application filed October 27, 1911. Serial No. 657,166.

To all whom it may concern:
Be it known that I, GEORGE H. WHEARY, a citizen of the United States, and resident of Racine, in the county of Racine and State of Wisconsin, have invented new and useful Improvements in Wardrobe Grips or Trays, of which the following is a description, reference being had to the accompanying drawings, which are a part of this specification.

My invention has relation to improvements in wardrobe grips or trays. The object of the invention is to provide a construction of such character that the grip or tray can be readily placed in or removed from a trunk body, and when removed can be placed vertically on end, and firmly supported in such vertical position for use as a wardrobe, the interior of the grip or tray being preferably provided with a complete hanger outfit. The grip arrangement is also such that the said grip can either be carried in a trunk for ready removal therefrom, or can be carried separately in traveling, the same as an ordinary dress suit case, and conveniently placed beneath the seat of a railway train, or beneath the berth of a steamer, and, upon the place of destination being reached, can be set up in a room for use as a wardrobe.

With the above primary, and other incidental objects in view, the invention consists of the devices and parts, or the equivalents thereof, as hereinafter more fully set forth.

In the accompanying drawings, Figure 1 is an elevation of the grip set up and supported vertically for use as a wardrobe; Fig. 2 is a horizontal section on the line 5—5 of Fig. 1. Fig. 3 is a vertical section of a fragment of the grip or tray, showing in full lines the supporting mechanism in operative supporting position, and in dotted lines in non-supporting position; and Fig. 4 is a front view of the tray showing the supporting mechanism adjusted to its non-supporting position.

The grip form of the device, indicated by numeral 13, is of the ordinary shape of a full dress suit case, being of rectangular form, and provided with a hinged lid or cover 14. When it is made for insertion into a trunk, the grip is somewhat larger than the ordinary size of a dress suit case. The grip is preferably provided within the

interior and the top portion thereof with a complete hanger outfit 15.

Mounted pivotally on trunnions or pivot pins 16—16 extending laterally and inwardly from the inner sides of the grip or tray, and near the lower end thereof, when the latter is set up in vertical position, are arms 17—17. Each of these arms is provided with an offset or shoulder 18, which permits the lower edge of the arm to rest upon the floor, when each arm is turned outwardly and downwardly to its horizontal supporting position, and at the same time clear the bottom end of the grip or tray, the offset being sufficiently great to accommodate trunk ends of varying thicknesses. In other words, the offset portion is shown in the drawings as some little distance above the bottom of the grip or tray, so that if the arms are applied to a grip or tray in which this bottom or end portion is of greater thickness, the arms will still be adapted thereto. These arms 17 are connected at their outer ends by a cross-piece 19, and said arms have also projecting from their outer sides hooks 20. Pivoted to the arms, just in advance of the shoulders 18, are links 21—21, provided with elongated slots 22—22. The sides of the grip or tray also have pins 23—23 extending inwardly therefrom and through the slots 22. The inner ends of the slots 22 have projecting therefrom short branch slots 24, which, in conjunction with the slots 22, form in effect a bayonet slot, so that when the arms 17 are turned outwardly and downwardly to the horizontal position shown in Fig. 3, with the cross-piece 19 resting upon the floor, the pins 23 are automatically engaged with the branch slots 24, and consequently the supporting device is held releasably locked in its supporting position.

The tray 25, illustrated specifically in Fig. 4, is provided interiorly with precisely the same hanger arrangement 15 as the grip 13, and also with precisely the same supporting mechanism, consisting of the arms 17 provided with hooks 20, the cross-piece 19, and the slotted links 21, arranged and connected as hereinbefore fully pointed out. The only difference between the two structures is that the tray is provided with an open top and is without the hinged lid or cover 14 of the grip. Therefore, in the case of the grip, when it is placed on end vertically, it is not

only supported by the supporting mechanism specifically described, but is also supported by the hinged lid or cover which is turned out at an angle, as clearly shown in 5 Figs. 1 and 2.

5 The improved grip and tray is adapted to be placed within a so-called steamer trunk, or within an automobile trunk, or for that matter is adapted for trunk purposes generally. When used in connection with, or placed within a steamer trunk the said trunk being of the proper height to fit beneath the berth of the stateroom, access can be obtained to the grip or tray by dropping down 10 the front lid or cover of the lid, and the grip or tray can then be readily drawn out, without the necessity of pulling the heavy trunk from beneath the berth. When the grip or tray is thus pulled entirely clear of 15 the interior of the trunk, it can be set up in any portion of the stateroom or other room, and be firmly supported in position to be 20 utilized as a wardrobe.

An automobile trunk is of such size to fit 25 not only on the rear of the automobile, but also on the running-board thereof, and when my improved form of grip or tray is used in connection with, or within such form of trunk, the said grip or tray, when a stopping 30 place is reached can be readily removed from the trunk and carried to the room of a hotel and set up for use as a wardrobe. Furthermore, in the grip form of the device the said device can be used entirely inde- 35 pendently of the trunk, as an ordinary suit case; that is to say it can be carried on a train or other conveyance, and when one's destination is reached it can be transported to the room of a hotel, and readily and 40 quickly set up on end for use as a wardrobe.

In the use of the grip or tray as a wardrobe, it is removed from the trunk by being merely pulled outwardly after first turning down the front lid or cover of the trunk. 45 The grip or tray is then set on end in a vertical position at any convenient point of a room. The cross-piece is next grasped, and the supporting mechanism pulled outwardly and downwardly to the supporting 50 position shown in Fig. 3, and when fully pulled out, the lateral projecting pins engage the branch slots 24 and thereby releasably lock the said mechanism in its supporting position. Now, if it is desired to hang clothes 55 on the hanger device, the user places the foot upon the cross-piece 19, and the grip or tray is thereby most firmly held and secured, even when the clothes are being arranged therein, and which operation, under ordinary 60 conditions, would have a tendency to tilt or upset the grip or tray. In order to restore the parts to normal position after the use of the device as a wardrobe is temporarily discontinued, the cross-piece is grasped and the 65 supporting mechanism turned back to the

position shown in Fig. 4, the inward movement of said mechanism being arrested by the engagement of the hook 20—20 with the edges of the grip or tray. When the supporting mechanism is thus turned back to 70 normal non-supporting position, the cross-piece 19 not only acts as a brace for the side of the grip or tray, but also serves as a clothes retainer, that is to say, it keeps the suspended clothes confined within the walls of the grip or tray. In the grip form, the door or lid 14 is also thrown out to the diagonal position shown in Fig. 2, and this assists the supporting mechanism in securing a firm support for the grip. In the case of 75 the tray form, as the door or lid 14 is not present, the said tray is, of course, without the additional support afforded by the door.

What I claim is:

1. The combination with a wardrobe section in the form of a casing, of movable supporting mechanism movably connected only at one end of the casing, and comprising side members movable together and located at opposite sides of the casing and adapted for supporting said casing at opposite sides thereof, the said members, when moved outwardly, leaving a clear or unobstructed entrance to the interior of the casing, and adapted, when so moved outwardly, to rest upon a floor, or other medium, and thereby support the casing in its upright position, and, when moved inwardly, to be adjusted to a position within the casing. 85

2. A wardrobe section, comprising a casing, and arms pivoted to the sides of the casing, near one end thereof, the said arms, when the casing is set up on the end where the arms are located, for use as a wardrobe, adapted, when turned outwardly and downwardly, to rest on a floor, or other medium, and to support the casing in its upright vertical position, and when the section is not in use as a wardrobe, to be turned upwardly to a position within the casing. 100

3. A wardrobe section, comprising a casing, arms pivoted to the sides of the casing, near one end thereof, said arms near their pivotal connections, being offset or shouldered on their lower edges to fit over the 105 end of the casing, and said arms, when the casing is set up on the end where the arms are located, adapted, when turned outwardly and downwardly, to rest on a floor, or other medium, and to support the casing in its upright vertical position, and when the section is not used as a wardrobe, to be turned upwardly to a position within the casing. 115

4. A wardrobe section, comprising a casing, arms pivoted to the sides of the casing, near one end thereof, said arms, when the casing is set up on the end where the arms are located, adapted, when turned outwardly and downwardly, to rest on a floor, or other medium, and to support the casing, and when 125

- the casing is not used as a wardrobe, the said arms adapted to be turned upwardly to a position within the casing, and a cross-piece connecting the outer ends of the arms 5 and resting on a floor, or other medium, when the arms are turned outwardly and downwardly, and having its ends fitting within and against the opposite sides of the casing when the arms are turned upwardly.
- 10 5. A wardrobe section, comprising a casing, arms pivoted to the sides of the casing, near one end thereof, pins or studs extending inwardly from opposite sides of the casing, slotted links pivoted to the pivoted arms, and 15 having the pins or studs extending through the slots thereof, the said pivoted arms, when turned outwardly and downwardly, and when the casing is set up on the end thereof where the arms are located, adapted 20 to support the casing in its upright position, and the slotted links adapted to hold or brace the arms in their supporting position, and said arms and links, when turned upwardly, adapted to be swung into the interior 25 of the casing.
6. A wardrobe section, comprising a casing, arms pivoted to the sides of the casing, near one end thereof, pins or studs extending inwardly from opposite sides of the casing, slotted links pivoted to the pivoted arms, and having the pins or studs extending through the slots thereof, the said slots 30 at their inner ends having short branch slots extending therefrom, and the said pivoted arms, when turned outwardly and downwardly, and when the casing is set up on the end thereof where the arms are located, adapted 35 to support the casing in its upright position, and the slotted links adapted to hold or brace the arms in their supporting position, the pins or studs at this time engaging the branch slots at the inner ends of the slots of the links, and when turned upwardly, adapted to be swung into the interior 40 of the casing.
7. A wardrobe section, comprising a casing, arms pivoted to the sides of the casing, near one end thereof, said arms, when the casing is set up on the end thereof where 45 the arms are located and for use as a wardrobe, adapted, when turned outwardly and downwardly, to rest on a floor, or other me-
- dium, and to support the casing in its upright vertical position, and when the section is not in use as a wardrobe, adapted to be 55 turned upwardly within the casing, and hooks secured to the arms, and adapted, when the arms are turned upwardly, to engage the edges of the sides of the casing.
8. A wardrobe section, comprising a casing, arms pivoted to the sides of the casing, near one end thereof, pins or studs extending inwardly from opposite sides of the casing, slotted links pivoted to the pivoted arms, and having the pins or studs extending 60 through the slots thereof, the said pivoted arms, when turned outwardly and downwardly, and when the casing is set up on the end thereof where the arms are located, adapted to support the casing in its upright 65 position, and the slotted links adapted to hold or brace the arms in their supporting position, and said arms and links, when turned outwardly, adapted to be swung into the interior of the casing, and a cross-piece 70 connecting the outer ends of the arms, and adapted, when said arms are turned outwardly, to rest on the floor, or other medium, and when the arms are turned upwardly adapted to have its ends fit within and to 75 bear against the opposite sides of the casing.
9. The combination of a wardrobe section in the form of a casing, a hinged cover for said casing, and movable supporting mechanism movably connected only at one end of 80 the casing, and comprising side members movable together and located at opposite sides of the casing and adapted for supporting said casing at opposite sides thereof, the said members, when moved outwardly, leaving 85 a clear or unobstructed entrance to the interior of the casing, and adapted, when so moved outwardly, to rest upon a floor, or other medium, and thereby, in conjunction with the outswung hinged cover, support 90 the casing in its upright position, and, when moved inwardly, to be adjusted to a position within the casing.
- In testimony whereof, I affix my signature, in presence of two witnesses.
